UNITED STATES PATENT OFFICE.

WILLIAM A. COATES, OF CHARLTON-CUM-HARDY, ENGLAND, ASSIGNOR TO WESTINGHOUSE ELECTRIC & MANUFACTURING COMPANY, A CORPORATION OF PENNSYLVANIA.

TRIP-FREE MECHANISM FOR TANK CIRCUIT BREAKERS.

Application filed September 19, 1922, Serial No. 589,057, and in England September 29, 1921.

My invention relates to operating mechanisms for electric circuit interrupters, particularly to circuit interrupters having relatively movable contact members operating in liquid baths.

One object of my invention is to provide a quick-acting circuit interrupter.

Another object of my invention is to provide a trip-free device which permits separation of the contact members independently of the link mechanism for effecting engagement thereof.

A further object of my invention is to provide a circuit interrupter in which the separation of the contact members is not hindered by the inertia of an attached train of mechanical links.

It is also an object of my invention to provide a pair of relatively movable contact members adapted to take advantage of the magnetic blow-out force exerted by the arc stream during the separation of such members.

In large capacity oil or other liquid switches, the short-circuit currents are often sufficiently heavy to set up strong magnetic fields having a repelling or deflecting action upon the switch contacts and throwing such considerable extra loads upon the operating mechanism, as will cause the latter to deflect and permit the switch contacts to open slightly before the automatic release of the switch has operated.

Switch operating mechanism of this character is commonly provided with a retaining catch adapted to hold the switch with the necessary pressure in the closed position and with a second trip catch forming what is generally known as a "loose handle" device which is interposed between the switch operating mechanism proper and the actuating member or handle.

This arrangement permits the switch to be opened either positively by moving the actuating member or handle whereby only the retaining catch is released or by means of a device adapted to release the trip catch and subsequently the retaining catch and thereby also release the operating mechanism proper from the actuating member or handle, a spring being generally provided to assist or accelerate the opening movement.

According to the present invention, with a view to obtaining a quick opening of the

switch, the trip catch is located immediately above the switch rod or element carrying the bridge or moving contacts so that, when the catch is tripped, the switch is permitted to open independently of any movement of the operating mechanism.

The tripping catch comprises a releasable coupling arranged substantially immediately above the vertically moving switch rod or element and adapted directly to connect the end of the latter to the operating mechanism to permit the switch to be closed and to be held in the closed position by means of a retaining catch and adapted, when tripped, completely to disconnect the said rod or element so that the switch is permitted immediately to open and is not subject to any delay which might be due to movement of the operating mechanism. Means are provided for automatically tripping the retaining catch after the switch has opened and for reconnecting the switch rod to the operating mechanism by means of the aforesaid coupling in readiness to permit the switch to be closed.

Any suitable form of retaining catch may be employed and it is preferably applied to a part of the switch-operating mechanism which is substantially in the plane of the movement of the switch rod so that the force required to retain the switch in the closed position is not transmitted through the link-work of the operating mechanism. The catch advantageously comprises a toggle strut pivotally connected, at one end, to a fixed part of the switch and, at the other end, to the operating mechanism at a point on the latter which is adjacent to the releasable coupling. On closing the switch, the toggle strut is adapted to be carried over its dead center to engage a fixed stop. A tie link is attached to the toggle strut and is so disposed that, when the switch is tripped, the link is engaged by the switch rod during its opening movement and the toggle is broken, causing the operating mechanism to collapse and follow the switch rod.

In order that the nature of the invention may be clearly understood, it will now be described with reference to the accompanying drawings, in which

Figure 1 is a front elevation, partly in section, of the upper part of a three-phase electric switch provided with operating

mechanism in accordance with the invention;

Fig. 2 is a side elevation of the device shown in Fig. 1, looking in the direction of the arrow II (Fig. 1);

Fig. 3 is a view similar to Fig. 2 but showing the operating mechanism in another position;

Fig. 4 is a sectional view on the line IV—IV, Fig. 1, looking in the direction of the arrow, certain parts being omitted for the sake of clearness;

Fig. 5 is a view similar to the right-hand portion of Fig. 2, parts being in section on the line V—V, Fig. 1;

Fig. 6 is a sectional view of a detail hereinafter explained; and

Fig. 7 is a view illustrating a modified form of the invention.

Referring now to Figs. 1 to 6 of the drawings, the rods 11, 12 and 13 which actuate the moving contact or bridge pieces of the respective phases are connected to a common cross-bar 14 which is constrained to move in a vertical direction by any suitable means. The cross-bar is rigidly attached to a frame 15 by two switch rods 16 and appropriate nuts 17, the upper part of the right-hand rod 16 and the end of the frame 15 being clearly shown in the detail view, Fig. 6. The frame 15 is of a trough-like or cradle form open at the top, as shown in Figs. 4 and 5, and rotatably supports two shafts 18, 19 mounted parallel to each other (see Figs. 4 and 5).

Substantially midway of the length of the shafts, triggers 20, 21 (see Fig. 4) are firmly secured to said shafts, respectively, the ends 22, 23 of the triggers being adapted, in one position of the parts, to engage rollers 24, 25 carried on a bell-crank lever 26 also pivoted to the frame 15, or a projection therefrom, by a pivot 27. The ends of the two triggers may be connected by a comparatively light spring 28 and, in the position shown in Fig. 4, prevent the shafts from rotating in the direction of the arrows when the switch is open.

At each end of each shaft a part is removed, as indicated at 29 (see particularly Figs. 5 and 6), so as to leave flat portions 30 which, in the position of the parts shown in Figs. 4, 5 and 6, are horizontal and rest on two stirrups 31 adapted to slide in orifices 32 in the frame 15, one of such orifices being shown in Fig. 5. These stirrups are slightly less in width than the distance between the axes of the shafts 18 and 19, as will be clear from Fig. 5, and are suspended by means of rods 33 from the horizontal rod 34 which is journaled in the last member 35 of the link mechanism.

It will be seen that the cross-bar 14 from which the switch rods are suspended is supported by the rods 16 from the frame

15, the weight being ultimately borne by the shafts 18 and 19, the flat portions 30 of which rest on the tops of the stirrups 31. The reactions at these points, therefore, tend to rotate said shafts in the direction of the arrows shown in Fig. 5, but this rotation in the position shown is prevented by the engagement of the ends of the triggers 22, 23 with the rollers 24, 25.

The operating linkwork for closing the switch is indicated generally by the numeral 36 and is pivoted at fixed points 37, 38 in the framework of the switch. The link mechanism is duplicated at each end of the rod 34, as shown in Fig. 1, and is so proportioned that the rod 34 is constrained to move in a straight vertical direction. Said linkwork may be operated to raise the stirrup 31 by pressure applied in an upward direction at the point 39 by any suitable mechanism (not shown) to cause the link 40 to rotate in the counter-clockwise direction around the pivot 37 and, in the raised position, a roller at the point 39 may be engaged by a retaining trigger 41 to hold said linkwork in this position. For the purpose of tripping the lever 26, a solenoid 42 having a movable core 43 is provided, the upward movement of which acts on a bell-crank lever 44 pivoted at a fixed point 45 to cause the end 46 of said lever to strike the end 47 of the trip lever 26 and rotate it in the clockwise direction, thereby disengaging the rollers 24, 25 from the triggers 22, 23.

The operation of the switch is as follows: assuming that the various parts occupy the positions shown in Figs. 1 to 5, in which positions the switch is closed, the cross-bars 14 being raised, if the solenoid 42 is energized, the movable core 43 is raised, thereby causing the release of the triggers 22, 23 as above described. The upward pressure of the stirrups 31 on the horizontal surfaces 30 of the shafts 18 and 19 will rotate these shafts in opposite directions, as shown by the arrows in Figs. 4 and 5, and, when said surfaces 30 become nearly vertical, the frame 15 will be released and move downwards, thereby causing the cross-bar 14 to descend and open the switch. During the descent of the rods 16, the projections thereon strike the lever 41 and rotate said lever on its pivot in a clockwise direction, thereby releasing the link 40. This permits the linkwork 36 to collapse and take the position shown in Fig. 3. The trip lever 26, being no longer in engagement with the end of the bell-crank lever 46, will permit the triggers 20, 21 to return to the positions shown in Fig. 4 under the action of the spring 28, and the surfaces 30 will re-engage with the upper ends of the stirrups 31.

To close the switch, an upward pressure

is applied at the point 39 to restore the link-work 36 to the position shown in Fig. 2, and the locking lever 41 will re-engage to hold it in this position. The upward movement of the rod 34 will move the stirrups 31 upwards and, by reason of their engagement with the shafts 18 and 19, will move the frame 15 upwards, thereby closing the switch.

10 In order to assist the switch in opening, a spring 50 may be provided at a suitable point, for example, between the cross-bar 14 and the framework of the switch, and a spring 50a may be provided to rotate the lever 41 to its locking position, shown in

15 Fig. 2.

It will be observed that the action of the trip lever 26, in opening, immediately effects the release of the coupling between the rods 16 which are attached to the cross-bar 20 and the stirrups 31 which are attached to the rod and that this coupling is arranged immediately above said rods so that the switch is permitted to open without any 25 delay which might be due to movement of the operating mechanism, namely, the link-work 36. By this means, a greater operating speed is obtained when the switch is tripped, as no portion of the mechanism, except the cross-bar and the switch brushes 30 themselves, is moved, which is a most important advantage.

In place of the retaining lever 41, any suitable form of catch or retaining device 35 may be employed. Preferably, however, such catch is applied to a part of the switch-operating mechanism which is substantially in the plane of the movement of the switch rod 16 so that the force required to retain 40 the switch in the closed position is not transmitted through the linkwork of the operating mechanism.

Fig. 7 illustrates another form of my invention in which a lever 48, corresponding 45 to the lever 41, is struck by the fall of member 15. Instead of collapsing the entire toggle mechanism, as is done in the modification shown in Figs. 2 and 3, a joint is broken by link 49 drawing links 51 and 50 52 out of alignment. The operation of the remaining parts of the device is the same as in the first modification.

It is to be understood that such variations 55 may be made in the details and arrangement of parts of my invention as fall within the spirit and scope of the appended claims.

I claim as my invention:—

1. In a circuit interrupter, a releasing

mechanism comprising a pair of parallel rollers having portions of their surface constituting planes, a movable contact member held by said rollers, and means for operating said rollers whereby said contact member is released.

2. In a circuit interrupter, the combination 65 with a movable contact member, a rod supporting said contact member, and a link mechanism for moving said supporting rod in a vertical direction, of a releasable tripping coupling located between the supporting 70 rod and the operating linkwork substantially immediately above the vertically moving supporting rod for permitting the switch to open independently of any movement of said operating linkwork, a retaining 75 device adapted to maintain the operating linkwork in the position which it assumes when the switch is closed, said retaining device being tripped during the opening movement of and by the supporting 80 rod and contact member to cause the operating linkwork to collapse when the switch has reached its open position.

3. In a link mechanism, a tripping means 85 comprising a pair of horizontal rollers, a trigger mounted on each roller, means for releasing said triggers, semi-circular portions of said rollers being cut away, supporting members bearing on the remaining portion of the rollers, whereby the rollers 90 are adapted to roll free from said supporting members upon the release of said triggers.

4. In a link mechanism, the combination 95 with a linkwork, and a member supported by said linkwork, of a releasing means for liberating the supported member independently of the linkwork, and means for collapsing said linkwork during the fall and 100 by the force of said supported member.

5. In a releasing mechanism, a pair of rotatable parallel members, supporting means bearing on said rotatable members, semi-circular portions of material being cut away 105 from said rotatable members at the bearing points to form flat faces, whereby said rotatable members may roll from the supporting means and fall, the supporting means remaining between the flat faces of said rotatable members during the downward movement of the rotatable members.

In testimony whereof, I have hereunto subscribed my name this first day of September, 1922.

WILLIAM A. COATES.
